UNITED STATES PATENT OFFICE.

GEORGE F. NAUGEL, OF MEDFORD, MASSACHUSETTS.

BOOT OR SHOE.

Application filed August 2, 1923. Serial No. 655,230.

This invention relates to boots and shoes and to a method of making the same.

The manufacture of boots and shoes at the present time, and especially the production of welt shoes, owing to the complicated structure thereof, involves a very large number and variety of separate operations. As a result, the amount of labor and materials required for the production of a shoe is 10 comparatively large considering the character and the uses of the product. Any reduction, therefore, in the amount of materials used or any elimination of operations which will not deleteriously affect the appearance of wearing qualities of the shoe, will reduce the cost of manufacture and is 15 much to be desired.

The main object of my invention is the provision of a shoe of simplified construction which requires less materials and may be made in fewer operations than heretofore; thereby, effecting a large saving in cost of manufacture.

Another object of the invention is the provision of a boot or shoe so made that moisture cannot gain entrance through the stitching by which the upper is secured to the sole.

A further object of the invention is the provision of a method for making boots or shoes which is simple and yet efficient, which obviates many of the steps and processes now required in the making of shoes and which greatly reduces the cost of manufacture.

Other objects of the invention will be more specifically pointed out and described hereinafter.

One of the important features of my invention resides in attaching the upper directly to the outer sole, thereby obviating the use of an inner sole. Preferably this is accomplished by channelling the edge of the sole in such manner as to split the edge into two portions or tongues, inserting the edge of the upper into the channel and then securing it therein and to the sole by suitable stitching. This method greatly simplifies the construction of the boot or shoe and eliminates many of the operations now required, such for example as those relating to the inner sole and lasting.

In the drawings illustrating one form of the invention, Figure 1 is a view in perspective, looking downwardly, of the sole portion of the boot or shoe, made in accordance with my invention, with a portion of

an upper attached thereto and broken off at the toe; Fig. 2 is a similar view but from a lower horizon showing a complete toe portion of an upper attached to the sole; and Fig. 3 is a cross-sectional view of the same on line 3—3 in Figure 2.

Referring to the drawings, 5 designates an outer sole having a heel 6 attached thereto, and 7 designates the vamp of an upper, 8 the toe cap, and 9 the blucher points of the upper with a lacing 10. The sole of the boot or shoe is provided with a channel 12 formed along its entire edge which splits the edge into two portions or tongues 14 the inner portion and 16 the outer portion. The channel 12 is sufficiently wide and deep to receive and hold the edge 18 of the upper. The upper may be secured to the sole in any suitable manner and one such manner is shown in the drawings, (Figure 3) by stitching, which extends through the upper above the inner portion of the sole 14 down through that portion and through the edge 18 of the upper lying in the channel 12 and through the outer portion 14 of the sole 5.

The method of making a boot or shoe of the above construction is as follows. The outer sole may be made of any suitable soling material, such as leather or rubber or other material and is died out in the usual manner. The sole is then provided in its entire edge with a channel 12 extending inwardly a distance sufficient to receive and hold the edge of an upper. The channel may be formed either by merely splitting the edge of the sole or by cutting out a portion of the material to form a channel having a square inner end as shown in Figure 3 or in any other suitable manner.

The channel 12 may be located midway between the inner and outer faces of the sole or may be nearer one than the other dependent upon varying conditions.

After the channel has been formed, the edge of the inner tongue 14 of the split edge of the sole may be trimmed down to permit the outer tongue 16 to project beyond the upper after it is attached to improve the appearance of the shoe and to extend the tread surface of the sole beyond the upper.

The upper of the boot or shoe may be prepared in the usual manner and when completed the edge 18 to be attached to the sole may be trimmed off and if desired skived. Suitable marks may be placed on the upper to indicate the amount of turn in to lie in

the channel in order to attain the exact size of shoe desired.

The upper is then mounted upon the sole 5 and the edges are inserted into the channel 5 12 and stitched in place by the use of any suitable machine. Although any suitable method of stitching may be used for this purpose, I prefer to attach the upper by stitching 20 which passes through the edge 19 of the upper on both sides of the inner tongue 14, through said tongue and through the tongue 16 to the outer face of the sole 5. This method of stitching has certain advantages in that it holds the upper more 15 securely to the sole and renders the shoe waterproof by binding the edge of the upper tightly about the tongue 14 of the sole. To insure waterproof qualities and to facilitate the stitching operation, the channel 12 20 may, before the edge of the upper is inserted, be thoroughly cemented and allowed to dry to a tacky condition. Then, if the upper be mounted on the sole the cement will hold the edge of the upper in place 25 during the stitching and when thoroughly dry will form an efficient barrier to the entrance of moisture.

After the upper has been attached to the sole, the heel may be mounted in place 30 and the sole trimmed and the shoe then placed upon a last for the various finishing operations, such as monogramming, insertion of sock lining, cleaning, dressing and so forth.

35 Although my invention in its simplest form contemplates the use of a single sole, it is obvious that the sole may be made of a single piece or may be built up of different layers or an additional sole may be stitched thereto after or at the same time that the upper is attached.

It is to be observed that my method eliminates a great many of the operations now employed in manufacturing boots and shoes 45 and that therefore the cost of manufacturing is greatly reduced, which makes this form of construction especially adaptable to cheap shoes and to slippers, moccasins and stitch-downs. Since the stitching attaching 50 the upper to the sole is all on the outside of the shoe, it is in consequence far more waterproof than the ordinary welt shoe because any moisture which follows the line of stitching or the stitching holes from the bottom of 55 the sole, will come out on the outside of the upper where it is turned over the upper tongue of the sole. At the same time the turning of the upper around both sides of the upper tongue prevents any moisture getting 60 into the shoe between the edge of the upper and the upper tongue of the sole.

It is to be understood, of course, that the foregoing description is merely illustrative of one form of my invention and that the 65 invention is not to be limited thereto since

it may be embodied in various other forms of construction, all within the purview of the following claims.

What I claim is:—

1. The method of making boots and shoes 70 consisting in preparing a sole, splitting the edge of said sole into two tongues by forming a channel therein, inserting the edge of an upper in said channel and folding the upper around the inner tongue, and then securing the upper to the sole by stitching passing through the two tongues and through the portions of the upper on the opposite faces of the inner tongue.

2. The method of making boots and shoes 80 consisting in preparing a sole, splitting the edge of said sole into two tongues by forming a channel in said edge, inserting the edge of an upper in said channel and folding the upper around the inner tongue to engage 85 the outer face thereof, and then securing said upper to said sole by a row of stitching passing through said upper, said tongues and the edge of said upper within said channel.

3. A method of making boots and shoes 90 consisting in preparing a sole from suitable material, splitting the edge of said sole into two tongues by cutting a channel in said edge, trimming down the inner of said tongues but leaving the said channel sufficiently deep to receive and hold the edge of an upper, preparing an upper, inserting the edge of said upper within said channel and then securing said upper to said sole by stitching passing through said upper, 100 said tongues and the edge of said upper in said channel.

4. A boot or shoe comprising a sole member formed of a single piece of material having a channel cut in its edge forming two 105 integral tongues, said channel being sufficiently deep to receive and hold the edge of an upper, an upper having its edge turned around the inner of said tongues and inserted in said channel, and stitching passing 110 through said upper, the inner tongue, the edge of said upper in said channel, and the outer tongue, for securing said upper to said sole member.

5. A boot or shoe comprising a sole member formed of a single piece of material having a channel cut in its outer edge throughout its periphery forming two integral tongues, said channel being sufficiently 115 deep to receive and hold the edge of an upper, an upper having its edge turned around the inner of said tongues and inserted in said channel, and stitching passing through said upper, said tongues and the edge of said upper in said channel for securing said upper to said sole member.

In witness whereof, I hereunto set my hand this 27th day of July, 1923.

GEORGE F. NAUGEL.
